CONSTANT FLOW NONPULSATING PUMP

William H. Curtis, Elyria, Ohio, assignor to Curtis Pump Company, Dayton, Ohio, a corporation of Ohio.

Application April 25, 1938, Serial No. 204,168

10 Claims. (CL 103—136)

This invention relates to pumps and particularly to vane type rotary pumps wherein the outer ends of the vanes oscillate toward and away from the center of rotation of the rotor.

5 An object of the invention is to provide a pump of this character in which the volume of fluid transferred, from the low to the high pressure side of the pump, is exactly the same per unit of angular movement at any point in a revolution 10 of the shaft, to the end that there will be no pulsation in the delivery.

Another object is to provide a pump of this type wherein the oscillatory movement of the vanes is so governed that no sharp changes in 15 oscillatory velocity of the vanes will occur, to the end that no mechanically occasioned shock will be present even when the pump is rotated at exceptionally high speed.

In the art as now known, the two foregoing 20 objects have not been attained in one and the same pump, because achievement of the one produces a structure in which it is highly difficult to fulfill the other.

It is therefore another object of this invention 25 to provide a structure in which the two foregoing objects are attained, each without sacrificing full attainment of the other.

Further objects and meritorious features will 30 become evident as the invention is described in detail, reference being had to the drawings, wherein,

Fig. 1 is a section thru a rotary pump of that type now known in the art in which the attainment of non pulsating delivery may be had only by such modification in the structure as will cause 35 mechanical shock, and the elimination of mechanical shock may be effected only by permitting pulsating deliver. Fig. 1 is included for illustrative purposes only and not as a part of this invention.

40 Fig. 2 is a diagram of a developed portion of the interior of a pump cylinder applicable to the pump shown in Fig. 1, and used where non pulsating delivery is to be achieved and mechanical shock permitted.

45 Fig. 3 is a diagram of a developed portion of the interior of a pump cylinder applicable to the pump shown in Fig. 1, and used where mechanical shock is to be eliminated and pulsating delivery permitted.

50 Figs. 4, 5 and 6 are diagrams of a developed portion of the interior surface of a pump cylinder made according to this invention, with vanes positioned at different places in their travel across the developed surface. These diagrams 55 are intended to illustrate the operation of the structure shown in Fig. 7.

Fig. 7 is a cross section taken at 1—1 of Fig. 8 thru a pump made according to this invention, 60 the structure being such as to secure non pulsat-

ing delivery and at the same time be free from mechanical shock.

Fig. 8 is an axial section taken at 8—8 of Fig. 7 thru the improved pump structure.

Figs. 9 and 10 are side views of two of the 5 vanes.

Fig. 11 is a diagram employed to illustrate the mathematics of the curve of a portion of the interior of the pump cylinder.

Fig. 12 is a section thru a modified form of 10 pump in which the principles of this invention may be embodied.

Fig. 13 shows an optional form of vane having sealing members at the ends.

Similar numerals refer only to similar parts 15 throughout the several views.

Referring particularly to Fig. 1, the body 28 of a rotary pump has a circular bore 27 into which the pump cylinder 24 is press fitted. The rotor 26 is rotatable on a shaft 28 about the 20 center 0 which is also the center of the outside of the cylinder 24.

The rotor 26 is provided with slots 30 at right angles to each other and with vanes 32 and 34 which are slidably radially in these slots. The vanes 32 and 34 are cut away as at 36 to clear 25 each other, the cut away portion being sufficient to permit the maximum radial movement of the vanes without interference with each other.

The vanes 32 and 34 are longer than the rotor 30 diameter and consequently project radially therefrom, the bore of the cylinder 24 being so fashioned as to permit rotation of the vanes with the rotor. For convenience in description, the center lines of the vanes are designated by letters AD 35 and CF.

Since both ends of a vane must contact the cylinder at any point of rotation of the rotor, obviously the interior of the cylinder may not be round since $AD = CF = BE$. The cylinder bore is 40 in fact made with the arc AF equal to the radius of the rotor, the arc CD having a radius equal to the rotor radius plus the excess of the vane length over the rotor diameter, and the curves AC and DF being necessarily such as to pass thru B and 45 E respectively and such as to contact both ends of a vane at any point in its rotation. The arcs AF and CD both have their centers at 0 which is the axis of the rotor.

Now since the fluid occupying the space 38 is 50 bounded by two arcs having the same center, it follows that uniform rotation of a vane from C to D effects a uniform delivery of the fluid within the space 38 into the space 40, so that were this the only consideration, non pulsating delivery 55 would be achieved.

It must be noted however, that while one vane is passing from C to D, another is passing from 50 D to F.

If a vane could pass from D to F without re- 60

tracting into the rotor, it would neither add to the volume in space 40 nor subtract from it, but the fact is, that while a vane passes from D to F it retracts into the rotor thereby increasing the space 40 by a volume equal to the volume of that part of a vane which extends from the rotor when the vane is at D. It follows that the delivery from the discharge end 42 per quarter turn of the rotor is equal to the fluid in space 38 minus a volume 10 of fluid equal to the vane extension at D.

It has been shown that the delivery of the fluid in space 38 is constant when the rotor speed is constant, that is, every degree of rotor rotation will transfer the same volume from 38 to 40 as every 15 other degree. It follows that if the ultimate discharge from the end 42 is to be constant, the vane extension must retract an equal amount per degree of turn, i. e., each degree of turn of the 90 degrees between D and F must retract the 20 vane extension $\frac{1}{60}$ of the whole retraction.

To satisfy the foregoing conditions mechanically, the cylinder curve from D to F must be plotted from a diagram as in Fig. 2, where the retraction velocity of a vane 32 between D and F 25 is exactly the same thruout, with uniform movement of the vane from D to F. In such a structure the vane 32 after moving from C to D without retraction, instantly changes at D from no retraction to the maximum rate of retraction. 30 and then without acceleration or deceleration maintains this constant rate of retraction from D to F, then at F instantly changes from the maximum rate of retraction to zero retraction.

If the curve from D to F were plotted on this 35 basis, the rotor could not be revolved at any practicable speed without destructive mechanical shock at points D and F.

It is therefore obvious that, in order to attain non pulsating delivery at the discharge end 42 40 an objectionable mechanical construction was necessarily adopted.

In order to avoid this mechanical shock, the curves of pump cylinders are usually plotted from a diagram as shown in Fig. 3. Here a vane 32 45 leaving point D, has a very small rate of retraction at the beginning, acceleration of retraction taking place between D and E where the maximum rate of retraction is reached. From E deceleration of retraction takes place until F is reached where 50 a zero rate of retraction is again had.

This acceleration and deceleration of the rate of retraction, however, provides a decided pulsation in the fluid delivery particularly in noncompressible fluids for it will be recalled that for 55 non pulsating delivery it was required that there be no acceleration or deceleration in the rate of retraction of a vane passing from D to F, but that the rate of retraction must be constant between these points in order that the ultimate 60 discharge at 42 may be constant and therefore without pulsation.

It will be seen that a structure which provides non pulsating delivery is subject to mechanical shock and that a structure which avoids 65 this mechanical shock introduces a decided pulsation into the delivery. It is therefore necessary, in employing existing art, to make a choice as to which of the two evils is to be endured, or provide a new structure not heretofore known 70 which eliminates them both. Such a new structure is the substance of this invention and will now be described.

Referring now to Figs. 7 to 10, a pump body 46 has a circular bore 48 with a pump cylinder 50 75 press fitted therein. An end head 51 is held to

the body 46 by screws 53 thereby closing the one end of the body.

The rotor 52 comprises a ring which is slotted at 60 degree intervals leaving a series of segmental lugs 54 between which the three vanes 56, 58 and 60 are transversely slidable.

The lugs 54 are formed integral with a disc 62 from which the shaft 64 extends, the shaft having rotative bearing in the hub 66 of body 46. The vanes are notched out to clear each other, 10 the vane 56 from the bottom upward as at 68, the vane 58 from the top downward as at 70, the vane 60 being notched from both top and bottom as at 72 and 74 Fig. 8. The vanes 56, 58 and 60 are longer than the diameter of the rotor and consequently project radially therefrom.

The axis of the rotor 52 and the axis of the outside of the cylinder 50 coincide at 0, but the inner contour of the cylinder is offset with the outside to such an extent that when the rotor 20 touches one side of the cylinder bore it is as far from the opposite side as the difference between the rotor diameter and the vane length. The center lines of the vanes are designated by letters AD, BE and CF.

Since $AD=BE=CF$ is obvious that the cylinder bore 48 may not be round. The cylinder bore is composed of an arc AF drawn to the radius of the rotor, an opposite arc CD drawn to a radius which is as much longer than the radius of the 30 rotor as the difference between the rotor diameter and the vane length, and the curves ABC and DEF which must be such that a straight line drawn from any point on ABC thru 0 to its intersection DEF will equal $AD=BE=CF$.

The cylinder 50 is slotted at 76 and 78 to provide suction and discharge ports respectively, the slots being of considerably less width than the cylinder, leaving ample bearing for the ends of the vanes to contact when passing over the 40 ports. Both parts 76 and 78 subtend an angle of 120 degrees centered at 0.

It has heretofore been shown that, in order to attain non pulsating delivery in the pump 45 shown in Fig. 1, the curve DEF must be plotted from the straight line DEF Fig. 2; that such a curve would produce objectionable mechanical shock; and that if the curve DEF was plotted according to the line DEF, Fig. 3, to avoid mechanical shock, an objectionable pulsation in the 50 delivery would inevitably result.

It is now the purpose to show how and why the curve DEF, Fig. 7, may be plotted according to lines DEF in Figs. 4, 5 and 6 to avoid mechanical shock, and at the same time secure 55 non pulsating delivery.

The line DEF, Fig. 4 represents diagrammatically the curve DEF Fig. 7, a vane 58 being positioned at D and a vane 60 at E. When the vanes 58 and 60 move laterally in the direction 60 of the arrow 80 across DEF, obviously they will retract vertically in the direction of the arrow 82. It will be observed that when the vane 58 first moves laterally away from D the rate of vertical retraction is very small per unit of lateral movement, but that the farther lateral movement progresses the more rapid the rate of vertical retraction until the vane 58 reaches E as in Fig. 6. At E the rate of vertical retraction is at a maximum and begins to diminish with 70 further lateral movement of the vane. Thus there is acceleration of vertical retraction from D to E and deceleration or negative acceleration of vertical retraction from E to F.

Now it will be observed that, since the vanes 75

are spaced 60 degrees apart and the curve DEF extends over 120 degrees, there are at all times two vanes within the extremities of the curve. It will be further observed that when a vane 58 leaves the point D, where the rate of retraction is lowest, the vane 60 is leaving E where the rate of retraction is highest (see Fig. 4), and when vanes 58 and 60 are midway between DE and EF respectively the rate of retraction is the same for both vanes (see Fig. 5), and that when the vanes 58 and 60 are at E and F respectively, the rate of retraction of vane 58 is highest and of vane 60 lowest.

The curve DEF must therefore be so formed throughout its 120 degrees that the 60 degree spaced vanes will at any stage in their movement across the curve have a rate of retraction in one vane as much below the average rate as the rate of retraction of the other vane is above the average rate, i. e., when the retraction rate is being accelerated in one vane it is being decelerated or negatively accelerated in the other. Stated in another way, if the sum of the two vane retractive velocities is to be constant, the algebraic sum of the accelerations of retraction of the two blades which are at the same time on the curve must equal zero, and the form of curve required is one, the equation of which will have its second derivative equal to a constant. This obviously indicates a parabola.

Two forms of polar equations, which are the most convenient in the analysis, are well known and applicable:

$$(1) \quad r = a\theta^2 + c$$

$$(2) \quad r = a\theta^2 + b\theta + c$$

It remains to select the equation best suited to the problem.

Referring to Fig. 11, AD, BE and CF represent constant length blades of zero thickness, and having in this instance an equal angular spacing of 60 degrees. AF is an arc with radius AO=FO, and CD is an arc with radius CO=DO. Since the vanes are to be of constant length, and the center line of any vane must always pass thru 0, it is required only to develop the portion AB of the curve, from which DE may be obtained by subtracting the respective AB ordinates from the constant representing the blade length.

EF and BC may then be obtained by symmetrical disposition of the values of AB and DE with respect to the vertical axis MN.

Two boundary values for the curve are obvious from the figure. At A the polar ordinate r must equal AO, the radius of the rotor, and at B it must equal BO or one-half the vane length. Since only two boundary values are required, the simpler of the two equations may be used, i. e., (1) $r = a\theta^2 + c$ in which c is a constant=AO the radius of the rotor, θ equals the angle from AO in radians, and

$$a \text{ is a constant} = \frac{BO - AO}{\theta^2}$$

where θ =angle AB in radians.

The complete mathematics of the curve follow:

$$r = a\theta^2 + c$$

$$\frac{dr}{d\theta} = 2a\theta = \text{rate of } r \text{ with respect to } \theta.$$

$$\frac{d^2r}{d\theta^2} = 2a = \text{acceleration of } r \text{ with respect to } \theta.$$

If θ represents angular velocity of blade and is uniform, it may be replaced by t =time, and

$$\frac{dr}{dt} = 2a\theta = \text{velocity of blade (retractive),}$$

$$\frac{d^2r}{dt^2} = 2a = \text{acceleration of blade (retractive),}$$

which are the respective velocities and accelerations of retraction in either zones AB or FE depending on the direction of rotation.

Also the corresponding polar ordinates for zones DE and BC are equal to $L-r$ where L equals the vane length, and if we let y equal the ordinate

$$y = L - a\theta^2 - c$$

then

$$\frac{dy}{d\theta} = -2a\theta$$

$$\frac{d^2y}{d\theta^2} = -2a$$

which shows that the relative velocities and accelerations in these zones are equal to those in the primary zones but opposite in sign. This must be true for otherwise vanes of constant length could not be used.

Now let us apply the actual condition in a pump of the form of Fig. 7, having counter clockwise rotation with inlet port extending from A to C, and discharge port extending from D to F.

Assume vanes D and E to have moved to D₁ and E₁ (see Fig. 11) and still in motion. Then the sum of their retractive velocities is

$$2a(\theta_1 + \theta_2)$$

which is obviously a constant for any position of D and E, in the zone DEF, since $\theta_1 + \theta_2$ = the angle DOE in radians = a constant. The condition still holds true when D₁ reaches the position E, for then θ_1 = radians DOE and θ_2 = zero.

Moreover the acceleration of D and E, with respect to each other are plus 2a and minus 2a which algebraically equal zero. Stated otherwise there is constant acceleration in zone DE and constant deceleration in zone EF, while at points D, E and F there is neither acceleration or deceleration.

Thus a curve is provided in which all of the conditions for uniform non pulsating discharge are met. Also, since the effect is obtained by reason of constant retractive vane velocity summation, it is independent of vane thickness. The vane thickness will, of course, affect the volume discharged, the thicker the vane the smaller the volume discharged.

Obviously the number of vanes need not be confined to the six, i. e., three thru vanes shown, but may comprise any reasonable number greater than four single vanes or two thru vanes. The inlet and outlet ports must span two or a multiple of two vane angles, the curve of the equation one or more vane angles, the pumping zone arc less than one vane angle and the seal whatever remains of the bore.

It will be apparent that the vanes may comprise either thru vanes, as shown, or, may comprise the older type of vane construction in which single vanes in individual slots are urged against the cylinder bore by springs or similar means placed between them.

For simplicity in illustration, in the embodiment shown, plain vanes with rounded ends are employed, but obviously vanes fitted with rock-

ers 84, Fig. 13, may be employed to good advantage, since the rockers have the capacity to adjust themselves to the varying curvature of the cylinder bore and thereby reduce the vane to a theoretical plane having length BE.

Where such rockers are not used it may be necessary to adjust the curves of the cylinder bore to allow for vane thickness, as otherwise the vanes would be more or less sharp at the ends on the center line. It is entirely possible, however, to employ vanes with appropriately rounded ends and retain all the advantages of this invention if suitable adjustments are made in the theoretical cylinder bore to compensate for the curvature on the vane ends, as by drawing, from a theoretical bore, a series of small arcs with radius the same as the vane ends, and fitting an actual bore to the outside of these small arcs.

20 The modification shown in Fig. 12 is shown to illustrate how the invention may be applied to a balanced rotor type of pump. Here a pump body 86 has a circular bore 88 centered at O, the outside of a cylinder 90 being closely fitted therein.

25 The cylinder 90 is slotted to provide suction ports 92 and 94 and discharge ports 96 and 98, which communicate respectively with passages 100, 102, 104 and 106 in the body 86.

30 The cylinder ports are so spaced as to leave two opposite sealing portions 108 and 110, the curves of which are tangent, make a line contact therewith, and to the rotor at C and H and two opposite pumping zones 112 and 114 at right angles to the sealing portions. The center lines of the ten vanes are at AO, BO, CO, etc., the pumping zones 112 and 114 extending from A to J and from E to F respectively. Obviously the sealing zones or the pumping zones may be increased in angular extent by increasing the 35 number of vanes.

40 The rotor 116 is slotted to receive the vanes slidably. Single vanes are employed because, the distance C-H must of necessity be less than either A-F or J-E precluding the use of solid thru vanes. Any of the means commonly employed to keep the outer ends of the vanes in contact with the inner wall of the cylinder are applicable. In the embodiment shown, a pin 118 extends from each vane into an appropriately formed track in the bearing head for this purpose.

45 In this balanced pump, Fig. 12, the hydraulic loads are equal and opposite and therefore lighten the load on the rotor and bearings, which is highly advantageous where high pressures are involved.

50 The two suction passages may with appropriate structural design be combined into one, as may also the two discharge passages. The outer ends of the vanes may be arcuate as shown, or fitted with rocker seals 84, as in Fig. 13.

55 The curve ABC is developed in two sections, but with the same basic equation as heretofore employed.

60 $r_{CB} = c + a\theta^2$ where $c = CO$ = rotor radius and θ = the angle from CO toward BO in radians.

65 $r_{AB} = c_1 + a\theta^2$ where c_1 is the line AO radius and θ = the angle from AO toward BO in radians.

70 The constant a is calculated from the boundary condition that the vane must be at one-half retraction or extension, depending on the direction of rotation, at point B. The three remaining curves CDE, FGH, and HIJ are developed by

symmetry. The portions AJ and EF are circle arcs of not less than one vane span.

In order that these pumps may be operated at exceptionally high speeds, the cylinder bore must be free from sharp changes of curvature. This requires common tangents wherever the bore changes in contour. That common tangents exist in the bores described may be proven as follows:

Let ϕ equal the angle between r and the tangent to the curve, then

$$\begin{aligned} \tan \phi &= \frac{rd\theta}{dr} = \frac{c + a\theta^2}{2a\theta} \text{ in zone CB} \\ &= \frac{c_1 - a\theta^2}{2a\theta} \text{ in zone AB} \end{aligned}$$

At C and A, $\theta =$ zero, therefore

$$\tan \phi = \frac{1}{0} = \text{infinity}$$

20 and the curves have a common tangent with arc AJ and adjacent curve CD.

Also at point B, $c + a\theta^2 = c_1 - a\theta^2$ and θ equals the same value in each case, therefore the tangent angles are equal and the curves have a common tangent at B. Therefore the cylinder bore is without sharp changes in curvature. Moreover, a vane in passing from A to B is under constant acceleration, while in the passage from B to C it is under constant deceleration. By applying the same reasoning here used to a flow analysis of the pump of Fig. 7 it will appear that the algebraic sum of the accelerations acting upon the vane or vanes in the zone ABC is constant and equal to zero, therefore the sum of their retraction velocities must be a constant whereby non pulsating flow conditions are provided. By the same method it may be shown that common tangents exist at all juncture joints between calculated curves and circle arcs in the forms shown in Figs. 7 and 11.

35 It should be noted that in the type of pump herein disclosed, the vanes do not move radially in the rotor when under load, i. e., when passing thru the pumping zone, all sliding movement of a 40 vane in the rotor occurring when the vane is passing over a port and doing no work. Excessive loads between surfaces in rubbing contact are therefore avoided whereby wear is held at a minimum.

45 Further it should be noted that functions developed and proven for the discharge port zone exist with opposite sign but similar effect over the intake zone.

50 In the claims, two thru vanes will be referred to as four vanes and three thru vanes as six vanes, etc.

Having shown and described several embodiments of the invention,

I claim:

60 1. In a pump of the offset rotor sliding vane type, a pump body having a right somewhat cylindrical bore, a normal cross section of which is defined by two opposite concentric arcs of unequal radii, with vane extending and retracting curves joining adjacent ends of said arcs, there being tangents common to the arcs and curves at their points of juncture, a cylindrical rotor having a diameter of twice the smaller of the two radii, rotatably positioned with its axis at the centers of the arcs, said rotor having radial vane slots, vanes slidable in said slots, the number of vanes being an even number necessarily greater than four, the ends of the vanes being always in contact with said bore, the surfaces defined by

75

the arcs of the smaller and larger radii respectively constituting a sealing and pumping zone, each subtending any whole number of vane spans, and the surfaces defined by the vane extending 5 and retracting curves having ports circumferentially equal to said curves which must subtend at least two or a multiple of two vane spans, said curves being so formed that, with constant angular velocity of the rotor, there will be uniform acceleration of the movement of a vane in a slot 10 as the end of the vane passes over the first half of the curve and uniform deceleration of the movement of said vane in its slot as its end passes over the second half of the curve.

15 2. The structure defined in claim 1 with opposite vanes of the same rotor slot being formed integral.

3. In a pump of the sliding vane type, a pump body having a right somewhat cylindrical bore, 20 a rotor smaller than said bore rotatably mounted in said bore with at least one side of the rotor in contact with said bore to form a seal, said rotor having axially extending vane slots spaced around its periphery, vanes having their outer ends always in contact with said bore slideable in said slots toward or away from the rotor axis, the number of vanes being any number greater than four, said bore comprising at least one pumping zone, said zone being defined by a radius drawn 25 from the rotor axis but greater than the rotor radius and subtending an arc equal to not less than one vane span, and vane extending or retracting curves beginning at the ends of the pumping zone arc and ending in an arc defined by 30 the rotor radius, each of said curves subtending two or a multiple of two vane spans, there being common tangents at the points of juncture between the said curves and the said arcs, the surfaces defined by the vane extending and retracting curves having ports defined by the same span 35 as the curves, said curves being so formed that, with constant angular velocity of the rotor, there will be uniform acceleration of the movement of a vane in a slot as the end of the vane passes over the first half of the curve, and uniform deceleration of the movement of said vane in its slot as 40 its end passes over the second half of the curve.

4. The structure defined in claim 3 wherein the acceleration of the extension or retraction velocity of a vane begins when a vane starts over a port and remains constant until it reaches a point angularly midway in said port, whence deceleration of the extension or retraction velocity begins at the same rate as it leaves the said mid- 45

way point and remains constant until it reaches the end of said port.

5. The structure defined in claim 3 wherein the said extending and retracting curves are of such length and so formed and the vanes are so spaced 5 with respect thereto that when one vane is at a position which is causing minimum retraction velocity to a vane, another vane is at a position which is causing maximum retraction velocity to a vane. 10

6. The structure defined in claim 3 wherein the said extending and retracting curves are of such length and so formed and the vanes so spaced with respect thereto, that when one vane is leaving the zone wherein there is zero extension or 15 retraction velocity of a vane in its slot, another vane is entering a zone wherein there is zero extension or retraction velocity of the vane in its slot, and another vane is midway between the first and second said vanes and is leaving a point 20 on said extending or retracting curve where there is maximum extension or retraction velocity.

7. The structure defined in claim 3 wherein the extending and retracting curves are of such length and so formed and the vanes are so spaced 25 with respect thereto, that when two vanes are within the boundaries of the same curve, one is receiving acceleration of its velocity of sliding movement, the other is receiving deceleration of 30 its velocity of sliding movement and said acceleration and deceleration are always numerically equal.

8. The structure defined in claim 3 wherein the said extending or retracting curves are of such length and so formed, and the vanes are so spaced 35 with respect thereto, that when two spaced apart vanes pass over a curve and are thereby extended or retracted radially, the sum of their extension or retraction velocities at any point in the rotation of said vanes is a constant. 40

9. The structure defined in claim 3 wherein the extending and retracting curves are of such length and so formed, and the vanes are so spaced with respect thereto, that the sum of the extension or retraction velocities of all vanes which 45 may be passing over a curve at the same time is a constant.

10. The structure defined in claim 3 wherein the extending and retracting curves are of such length and so formed, and the vanes so spaced 50 with respect thereto, that the algebraic sum of all accelerations of extension and retraction velocities of all vanes passing at the same time over said curves is equal to zero.

WILLIAM H. CURTIS.

Certificate of Correction

Patent No. 2,165,963.

July 11, 1939.

WILLIAM H. CURTIS

It is hereby certified that errors appear in the printed specification of the above numbered patent requiring correction as follows: Page 2, second column, line 26, before the word "is" insert *is*; line 35, before "DEF" insert *with*; line 41, for the word "parts" read *ports*; page 3, second column, line 65, before "less" insert *not*; page 4, first column, lines 32 and 33, for the words "tangent, make a line contact therewith, and to the rotor at C and H and" read *tangent to the rotor at C and H and make a line contact therewith, and*; line 69, in the equation, for " $r_{AB} = c_1 + a\theta^2$ "; read $r_{AB} = c_1 - a\theta^2$; and second column, line 29, for "in the passage" read *in passing*; and that the said Letters Patent should be read with these corrections therein that the same may conform to the record of the case in the Patent Office.

Signed and sealed this 17th day of October, A. D. 1939.

[SEAL]

HENRY VAN ARSDALE,
Acting Commissioner of Patents.
